Patented Dec. 24, 1957

181,790

COMBINATION ADVERTISING DISPLAY AND GAME

Harold J. Gerber, Baltimore, Md.

Application November 22, 1955, Serial No. 38,991

Term of patent 7 years

(Cl. D1—2)

Fig. 1

Fig. 1 is a front perspective view of a combination advertising display and game showing my new design;

Fig. 2 is a rear perspective view, with rear cover removed, of the article of Fig. 1; and

Fig. 3 is a rear elevation of the article of Fig. 1 on a reduced scale.

I claim:

The ornamental design for a combination advertising display and game, as shown.
